WHEEL TRIM UNIT OR SIMILAR ARTICLE

George Albert Lyon, 13881 W. Chicago Blvd.,
Detroit, Mich.

Filed Nov. 12, 1959, Ser. No. 58,327

Term of patent 14 years

(Cl. D14—30)

Figure 1 is a side elevational view of a wheel trim unit or similar article embodying my new design:

Figure 2 is a profile view showing the cross-sectional contour of the wheel trim unit of Figure 1; and

Figure 3 is a fragmentary side perspective view of the wheel trim unit.

The broken line showing of a wheel and tire is for purposes of illustration only.

I claim:

The ornamental design for a wheel trim unit or similar article, substantially as shown and described.
